UNITED STATES PATENT OFFICE

CLYDE E. PLOEGER AND WILLIAM D. COLLINS, OF EVANSVILLE, INDIANA, ASSIGNEES
TO SERVEL INC., OF NEW YORK, N. Y., A CORPORATION OF DELAWARE

REFRIGERATION

Application filed October 27, 1930. Serial No. 491,427.

This invention relates to mechanical refrigeration, and more particularly to a method of mounting refrigerating apparatus so that it can be detachably assembled as a unit with a refrigerator.

It is contemplated by this invention that the evaporator is positioned within the refrigerating chamber of a refrigerator, the motor driven compressor unit and the condensers are in an apparatus chamber below the refrigerating chamber, and a flue in the rear of the refrigerator communicates with the apparatus chamber to induce a draft of air entering the bottom of the refrigerator for cooling the condensers and the motor compressor unit. It is desirable that the refrigerating apparatus be assembled as a single unit which is easily placed in position in the refrigerator and easily detached therefrom. To accomplish this there is provided a frame so constructed that the condensers and motor-compressor unit mounted on the base thereof will be positioned in the apparatus compartment and the evaporator mounted on the upper portion will be positioned in the refrigerating compartment when the frame with the apparatus mounted thereon, forming a unit, is assembled with the refrigerator.

The invention will be better understood by reference to the following description taken in connection with the drawings in which

Fig. 1 is a rear elevation of a refrigerating unit embodying this invention;

Fig. 2, a sectional view along the line

2—2 of Fig. 1;

Fig. 3, a side view partly in elevation and partly in vertical section showing the refrigerating unit positioned in a refrigerator cabinet;

Fig. 4, a fragmentary sectional view on the line 4—4 of Fig. 3; and

Fig. 5, a view similar to Fig. 2 showing a condenser of modified construction.

Referring to Figs. 1 and 2, the refrigerating apparatus is mounted on a frame comprising a base portion and a vertical portion. The base portion is fabricated of sheet metal plates 10, 11, 12 and 13, welded together to form a rectangular box structure

open at the bottom and top and plates 14 and 15 welded in place to form parallel partitions which divide this box structure into a central section and two equal end sections.

The partition plates 14 and 15 do not extend the full width of the side plates 11 and 13 but have portions 16 of extended width above the side plates as may be seen in Figs. 1 and 3.

The bottom of the central section of the base between the plates 14 and 15 is closed by a sheet metal plate 18 upon which a hermetically sealed motor-compressor unit 19 is suitably mounted and secured by bolts 20. A circular opening 21 is provided in the plate 18 directly under the motor-compressor unit to allow air coming through the bottom of the refrigerator to pass upwardly around the unit and through the radiating fins 22 for dissipating heat generated in the unit.

In the end section of the base between the end plate 10 and the partition plate 14 there is disposed a condenser which may consist of coils 23 formed of tubing wound back and forth through suitable openings in plates 11 and 13. The condenser is provided with transverse radiating fins 24 which extend across the coils between the end plate 10 and partition plate 14. A similar condenser is positioned in the end section of the base on the other side of the motor-compressor unit between end plate 12 and partition plate 15 and the two condensers are connected in series.

The vertical portion of the frame is composed of angle irons 17 welded or otherwise secured in a vertical position to the plates 14 and 15 at their extended portions 16. At the top of the vertical portion of the frame there is secured a section of heat insulated refrigerator wall 25 upon which the evaporator 26 is mounted as by lugs 42 in such a position that when the frame is secured in place in the refrigerator the evaporator will be positioned within the refrigerating chamber 27 and the wall section 25 will close an opening 28 in the refrigerating chamber wall 29 through which the evaporator was inserted.

5 A vapor suction line 30 connects the evaporator 26 and the intake 31 of the hermetically sealed motor-compressor unit 19 which 10 discharges compressed refrigerant vapor through conduits 32 to the condenser coils 24. Liquid refrigerant from the condenser is returned to the evaporator through conduits 33 and 34 between which there is a refrigerant supply control means 35.

10 15 20 25 The refrigerator may be of any well known construction comprising a refrigerating chamber 27 with heat insulated walls 29 and an apparatus space 36 immediately below the refrigerator chamber. An opening 28 is provided in the rear wall of the refrigerating compartment through which the evaporator is inserted when the apparatus unit is assembled with the refrigerator as explained herein. The apparatus space in the lower part of the refrigerator is open at the bottom and at the rear end is in open communication with a flue 37 which extends up the rear of the refrigerator and is formed between the wall of the refrigerating chamber and the sheet metal plate 38 suitably attached.

30 Referring to Figs. 3 and 4 of the drawings, when the refrigerating apparatus mounted on the frame and forming a single unit is assembled with the refrigerator, the flue casing 38 being removed, the apparatus unit can be inserted from the rear. When in position the base of the frame on which is mounted the condensers and the motor-compressor unit is within the apparatus chamber in the lower part of the refrigerator, the angle irons or vertical portion of the frame extend upwardly within the flue, the evaporator 26 is within the refrigerating 35 40 45 chamber 27 and the wall section 25 which carries the evaporator and is mounted on the upper part of the frame closes an opening 28 in the rear wall of the refrigerating chamber through which the evaporator was inserted.

50 A suitable gasket 39 between a ledge 40 around the opening in the refrigerator chamber wall and the closure member 25 seals the joint between the closure member and the wall.

55 60 65 The apparatus unit may be secured in any desired manner and the flue plate 38 placed in position. When the apparatus unit is thus assembled with the refrigerator there is a complete path for air circulation from the bottom of the refrigerator which is open, up through the condenser coils in the end sections of the base portion of the frame and upwardly through the flue in the rear of the refrigerator. As explained above, air for cooling the motor-compressor unit passes upwardly from the open bottom of the refrigerator through the opening 21 in the mounting plate 18, through the heat radiat-

ing fins 22 and up the flue 37 in the back of the refrigerator.

In a construction according to this invention air for cooling the condensers will not have previously been warmed by coming in contact with the motor-compressor unit and due to the draft induced by the flue at the back of the refrigerator air which has been utilized to cool the motor-compressor unit will not come in contact with the condenser coils, which is a factor conducive to high efficiency.

Obviously, many modifications may be made within the scope of this invention, for instance, as shown in Fig. 5 the base portion 80 may be modified by extending end plates 10 and 12 and adding member 41 to accommodate condenser coils 42 to afford greater condenser cooling surface. Conforming to the inventive thought in this arrangement also, 85 the air for cooling the condensers will not have been previously warmed by contact with the motor-compressor unit.

It will be obvious to those skilled in the art that various other changes may be made 90 in the construction and arrangement without departing from the spirit of the invention and therefore the invention is not limited to what is shown in the drawings and described in the specification but only as indicated in the appended claims.

We claim:

1. A refrigerator including an apparatus compartment, a flue extending therefrom and forming a continuous passage therewith, a refrigerating compartment above said apparatus compartment and formed in part by a wall having an aperture therein, a refrigerating unit including a frame, a compressor mounted on said frame, a closure 100 member for said aperture mounted on said frame, an evaporator supported by said closure member and adapted to be inserted through said aperture, condensers mounted on said frame, said refrigerating unit adapted to be secured in such position that the evaporator is within the refrigerating chamber, the closure member seals the aperture, the compressor is within the apparatus chamber and the condensers are within said 110 passageway.

2. A refrigerator including an apparatus compartment having air inlet openings therin, a vertical flue extending from said apparatus compartment, a refrigerating compartment positioned above said apparatus compartment and having an opening in a wall thereof, a refrigerating apparatus including a vertical frame, a compressor unit supported from the lower portion of said frame, a closure member for said opening mounted on said frame, an evaporator supported by said closure member and adapted to be inserted through said opening, condensers mounted on said frame in spaced hori- 120 125 130

zontal relation with said compressor, said refrigerating apparatus adapted to be secured in such position that the evaporator is within the refrigerating chamber, the closure 5 member seals the opening, and the compressor and condensers are within the apparatus chamber.

3. A refrigerator comprising, in combination, a cabinet structure including an apparatus compartment with one or more air inlet openings therein, a refrigerating compartment above said apparatus compartment and formed in part by a rear wall having an aperture therein, a vertical flue at the rear of said 10 compartments forming a continuous passage-way with the apparatus compartment for air from said inlet openings, a refrigerating unit including a vertical frame, a compressor unit supported from the lower part of said 15 frame, condensers supported by said frame in spaced horizontal relation with said compressor unit, a closure member for said aperture mounted on the upper part of said frame, an evaporator supported on said closure member and adapted to be inserted through said 20 aperture, connecting conduits between and control devices for said compressor, condensers and evaporator mounted integrally with said refrigerating unit, said refrigerating 25 unit adapted to be removably secured in said cabinet structure so that the evaporator is within the refrigerating chamber, the closure member seals the aperture, and the compressor unit and the condensers are within the 30 apparatus chamber.

4. A refrigerator including an apparatus compartment, a flue extending therefrom, a refrigerating compartment above said apparatus compartment, a frame, a refrigerating 40 unit mounted on said frame and including a compressor on the lower portion of the frame and an evaporator on the upper portion of the frame, said frame and refrigerating unit adapted to be secured in such position that the 45 evaporator is within the refrigerating chamber and the frame in the flue.

5. A refrigerator comprising a cabinet including an apparatus compartment and a refrigerating compartment above said apparatus compartment having an aperture in a wall thereof, and refrigerating apparatus including a condensing unit, a frame, and an evaporator supported laterally from said frame, said refrigerating apparatus adapted 55 to be removably secured as a unit in said cabinet, so that the evaporator extends into the refrigerating chamber through said aperture.

6. A refrigerator comprising a cabinet including an apparatus compartment and a refrigerating compartment above said apparatus compartment having an aperture in a wall thereof, and refrigerating apparatus including a condensing unit, a frame, and an evaporator supported laterally from said 60 frame, said refrigerating apparatus being re-

movably secured as a unit in said cabinet, with the evaporator extending into the refrigerating chamber through said aperture and the condensing unit disposed in the apparatus compartment.

70

7. A refrigerator comprising a cabinet having a refrigerating compartment and an apparatus compartment beneath the refrigerating compartment, said apparatus compartment being open at its bottom, and said cabinet having a flue extending upwardly from the apparatus compartment for creating a natural draft therethrough, and refrigerating mechanism removable as a unit from said cabinet, and including an evaporator for location in the refrigerating compartment and compressor condenser mechanism located in the apparatus compartment, said compressor condenser structure forming the bottom 75 of the cabinet.

80

8. A refrigerator cabinet comprising an apparatus compartment, flue means for drawing air through said compartment, and refrigerating mechanism including a condenser relatively flat in outline disposed substantially horizontally in substantially the lower portion of the apparatus compartment, and a compressor spaced substantially horizontally relative to said condenser.

85

9. A refrigerator cabinet comprising an apparatus compartment, flue means for drawing air through said compartment, and refrigerating mechanism removable as a unit from said refrigerator cabinet and including a condenser relatively flat in outline disposed substantially horizontally in substantially the lower portion of the apparatus compartment, and a compressor spaced substantially horizontally relative to said condenser.

95

10. A refrigerator having a refrigerating compartment, an adjacent apparatus compartment, a chamber extending from the apparatus compartment in overlapping relation to the refrigerating compartment, a removable refrigerating unit comprising a frame 100 for location in said chamber, and evaporating and condensing means connected in spaced relation to said frame.

105

11. A refrigerator cabinet comprising side walls and partition wall structure defining a refrigerating compartment and a second compartment extending on two sides of the refrigerating compartment, said partition wall structure being set in from the edges of the side walls, a removable plate at one side 115 of the second compartment for affording access to said compartment, a frame for location in said second compartment, and refrigerating mechanism for cooling the refrigerating compartment supported by said frame.
